PUMP OPERATING AND CONTROL MECHANISM FOR STEREOTYPE PLATE CASTING MACHINES

Isidor Tornberg, Plainfield, and Paul L. Tollison, North Plainfield, N. J., assignors to Wood News-paper Machinery Corporation, Plainfield, N. J., a corporation of Virginia

Application July 16, 1949, Serial No. 105,202

8 Claims. (Cl. 22—2)

1

This invention relates to stereotype plate casting machines, and more particularly concerns mechanism for pumping type metal into the mold space of a plate casting machine under control of the mold space forming mechanism.

Stereotype plates for printing are cast from type metal in plate casting machines. These comprise essentially a mold space formed between relatively movable parts comprising a concave casting box and a cylindrically surfaced core, a mat or matrix carrying the type impression being secured to the interior of the casting box and the metal being pumped into the mold space from the melting pot. In all but the largest installations the mold space is opened and closed and the metal is pumped by hand. Such manually operable machines are sometimes operated in improper sequence with consequent hazards of injury to operating personnel, damage to the machines and loss of operating time. For example, the pump may be operated with the mold space open, spilling molten type metal on the floor near the machine. Also, the pump may be operated a second time before removal of a previously cast plate from the mold space, with the result that the molten type metal overflows the mold and spills over the machine and to the floor. In many modern casting boxes, the matrix is held against the concave box surface by a vacuum applied through small holes in the concave surface of the box. If the operator pumps metal into the mold space with no matrix in the casting box, the molten metal is drawn into the vacuum holes and the machine is thus put out of operation until costly and time-consuming repairs have been made.

The present invention has for its object the provision of power operated metal pumping mechanism for stereotype plate casting machines incorporating devices which insure that the mold space is in proper condition to receive the molten type metal when the pump is operated. To this end, the mechanism of the invention provides controls which permit operation of the pump to deliver metal to the mold space only after the casting box and core are in closed relation to form the mold space and then only if a matrix is in place in the casting box. The mechanism of the invention also provides means for preventing a second mold charging operation of the pump until after the mold has been opened for the removal of the cast plate and thereafter reclosed.

In describing the invention in detail, reference will be made to the accompanying drawings, in

2

which certain embodiments of the invention have been illustrated.

In the drawings:

Fig. 1 is a plan view of mechanism incorporating the invention applied to a plate casting machine of the type employing a rotary cylindrical core and a laterally movable casting box;

Fig. 2 is an elevation of the mechanism shown in Fig. 1;

Fig. 3 is a sectional view taken along the line 3—3 of Fig. 1 and showing the type metal pot and pump in section;

Fig. 4 is a plan view of the mechanism taken along the line 4—4 of Fig. 3;

Fig. 5 is a sectional view of the air control valve taken along the line 5—5 of Fig. 4;

Figs. 6, 7 and 8 are elevations of the air control valve and its control mechanism taken along the line 6—6 of Fig. 4 and respectively showing the mechanism in the position occupied when permitting operation of the valve (Fig. 6) in the position occupied when the valve is operated to effect a mold charging stroke of the metal pump (Fig. 7); and in the position occupied when the valve is locked against operation;

Fig. 9 is a plan view of the casting box and core, partly in section, showing the vacuum control mechanism responsive to the presence or absence of a matrix in the casting box;

Fig. 10 is a diagrammatic representation of the pneumatic and electric connections of the pumping control mechanism;

Fig. 11 is an elevation illustrating a modified form of mechanism embodying the invention and applied to a plate casting machine of the type employing a semi-cylindrical core that moves to a substantially horizontal position to discharge a cast plate;

Fig. 12 is a plan view of the pump operating valve control mechanism of the embodiment of Fig. 11 taken along the line 12—12 of Fig. 11, the mechanism being shown in the position it occupies when the mold space is open and pump operation is prevented;

Fig. 13 is a plan view similar to Fig. 12 showing the mechanism in the position it occupies when the mold space is closed and pump operation is permitted;

Fig. 14 is an elevation, partly in section, taken along the line 14—14 of Fig. 13 and showing the air and vacuum control mechanism; and

Fig. 15 is a diagrammatic representation of the pneumatic and electrical connections of the modification of the invention illustrated in Figs. 11—14.

Referring to Figs. 1—4, inclusive, the plate cast-

ing mechanism includes a core 1 and a casting box 2, both disposed vertically of a suitable base 3. The core 1 is cylindrical and is rotatable about the axis of a central shaft 3 by a motor 4 through a shaft 5, a pinion 6 and a crown gear 7. A clutch comprising a movable collar 8 splined to the shaft 5 and engageable with a toothed member 8' fixed to the motor shaft controls the application of rotating power to the core. A pot 9 containing molten type metal 10 is located in a furnace 11 adjacent the mold-forming mechanism and a pump 12 of conventional construction is supported by a bracket 6 in a position below the metal surface in the pot. The pump 12 is provided with the usual piston 13, piston rod 14 and valve mechanism 15. A pump lever 16, pivotally supported by a stud 17, is connected to the piston rod 14 by links 18. A counterbalance 19 is carried by an extension of the pump lever 16, and a removable handle 20 may be provided to permit manual operation of the pump in emergencies. A power unit in the form of an air cylinder 21 to provide power for operating the pump is pivotally connected to an upstanding extension 22 of the bracket 6, and the piston rod 23 of this cylinder is pivotally connected to the pump lever 16, as shown. The construction of the air cylinder 21 is such that when compressed air is supplied to the upper end through the hose 24, the piston rod 23 is extended and the pump lever 16 is moved downward to perform a mold charging stroke of the pump 12, the magnitude of which stroke is adjustably limited by a stop screw 25. When compressed air is admitted to the lower end of the cylinder through the hose 26, the piston rod 23 is retracted, lifting the pump lever 16 and lowering the pump piston 13 in readiness for a subsequent mold charging stroke.

The mold space 27 in which the stereotype plates are cast is formed by the core 1 and the casting box 2 when in juxtaposition, as shown in Fig. 4, and this space is closed at its sides by matrix clips 28 of conventional construction. The molten type metal is introduced into the mold space through a spout 29 connected to the pump 12, as shown in Figs. 3 and 4. The mold space is opened to permit removal of a plate by moving the casting box 2 laterally away from the core 1 and this is accomplished by known mounting and moving means, shown in Figs. 1 and 2 and generally designated 30. When the mold space is opened, the core 1 is rotated through a half revolution to carry the cast plate to an exposed position, opposite the casting box, so that it can be removed from the core. This half revolution motion of the core is governed by clutch mechanism of known construction, which will now be described.

The movable collar 8 of the clutch is provided with a circumferential groove engaged by a roller 31 carried by a lever 32 having a handle 33. The lever 32 is carried by a fixed pivot 34. An extension of the lever 32 beyond the pivot 34 carries a roller 36 engaging a cam track 35 on a disc 37 located just below and rotating with the core turning crown gear 7, which rotates the core 1. Oppositely disposed notches 38 and 38' in the track 35 permit the lever 32 to move to a clutch disengaging position under the bias imposed by a suitable spring 39 when the roller 36 enters one of the notches 38 and 38'. This mechanism stops rotation of the core 1 at the successive positions where plates are discharged therefrom.

The normal sequence of operation of the cast-

ing machine thus far described is that after a plate is cast, the operator operates the mechanism 30 so that the casting box 2 is retracted from the core 1 and the newly cast plate carried on the core. The operator then moves the clutch handle 33 and permits the motor 4 to rotate the core 1 through a half revolution, as explained above. The operator then moves the casting box 2 back into mold forming relation with the core 1 by means of the mechanism 30, thus pushing the newly cast plate off of the exposed side of the core, and the mold space is then in readiness for casting the next successive plate.

In view of this sequence of operation, the rotation of the core through a half revolution makes it certain that the cast plate has been removed from the mold space.

Compressed air for operating the pump lever 16 by the air cylinder 21 is controlled by a valve V mounted on a stationary plate 40 carried by posts 41 secured to a flange 42 on the fixed hub in which the core shaft 3 rotates. The journals 44 that carry the shaft 5 are also carried by the stationary plate 40. The valve V has a compressed air inlet port 45 connected to an air pipe 46, an outlet port 47 connected to the hose 26 leading to the lower end of the air cylinder 21, an outlet port 48 connected to the hose 24 leading to the upper end of the air cylinder 21, and exhaust ports 49 and 50 connected to the atmosphere. A vertically slideable valve spool 51 carried by a central rod 52 slides vertically in the valve chamber and connects the inlet port 45 to the outlet port 47 when lowered as shown in Fig. 5, and connects the inlet port 45 to the outlet port 48 when raised by depressing the pivoted valve handle 53. A spring 54 surrounding the upper end of the rod 52 moves the spool 51 to the lowered position when the handle 53 is released. The outlet port 48 is connected to the exhaust port 49 when the spool 51 is lowered and the outlet port 47 is connected to the exhaust port 50 when the spool 51 is raised. Thus, by depressing the handle 53 and subsequently releasing it, compressed air is admitted or exhausted to move the pump lever 16 up for a mold charging stroke and then down for a return stroke.

In accordance with the invention, the operation of the valve handle 53 is governed by the operation of the core cylinder 1 and the casting box 2 in such a manner that two successive metal charges cannot be pumped into the mold space without an intervening cast plate removing operation. The mechanism illustrated for accomplishing this result is particularly illustrated in Figs. 2, 4, 5, 6, 7 and 8. Referring particularly to Fig. 6, a stop bar 54 is pivotally supported beneath the valve handle 53 and is biased by a spring 55 to move clockwise toward the vertical lever blocking position shown in Fig. 8. A pivoted latch bar 56 is biased clockwise by a spring 57 and its end 58 is engageable with a lug 59 on the stop bar 54, a second lug 60 on the stop bar limiting the clockwise movement of the latch bar, as shown in Fig. 6. A slideable pin 61 extends through the plate 40 on which the valve V is carried and the upper end of the pin lies beneath a foot 62 on the stop bar 54. The lower end of the pin 61 rides on the upper surface of the web of the crown gear 7 that rotates the core 1, and the pin is raised by either one of two diametrically opposite cams 63 and 63' carried on the crown gear web, as shown in Figs. 4, 5 and 6.

Assuming the parts to be in the position illustrated in Fig. 6, and further that the mold space 27 is closed and a matrix is in place in the casting box 2, when the valve handle 53 is depressed to cause a metal pumping operation, the latch bar 56 is moved down out of contact with the stop bar lug 59, and the stop bar 54 moves to the right in contact with the valve handle 53, as shown in Fig. 7. When the handle 53 is released and raised, the stop bar 54 moves to a vertical position beneath the handle (Fig. 8) and so prevents a second operation of the handle with resultant flooding of the mold with molten metal. After the stereotyped plate has solidified in the mold space, the casting box 2 is retracted and the core 1 rotated through a half revolution, as explained above. During the course of this core movement, one of the cams 63 or 63' lifts the pin 61 tilting the stop bar 54 out of the path of the valve handle 53 and engaging the latch bar end 58 with the lug 59 to hold the stop bar 54 in its retracted position. Since rotation of the core necessarily designates removal of the cast plate from the mold space, the valve handle 53 is released for further operation only after the cast plate has been removed.

Referring to Figs. 9 and 10, the casting box 2 is provided with a plurality of holes 65 on its inner face, all communicating with a manifold 66 connected by a pipe 67 with a suction mechanism or source of vacuum 68. According to the invention, a cylinder 69 is connected to the pipe 67 and a spring biased piston 70 in this cylinder is suitably connected to close the electrical contacts 71 when a vacuum is drawn in the manifold 66, and to open these contacts when no vacuum is so drawn. When a matrix 72 is in place in the casting box 2, it is drawn or seated against the inner surface of the box and closes the holes 65 so that a vacuum is drawn in the ducts comprising the manifold 66, pipe 67 and cylinder 69, moving the piston to the right when viewed in Fig. 9 and closing the contacts 71. If no matrix is in the casting box, the holes 65 are not closed, no vacuum is drawn and the contacts 71 remain open. A gauge 13 may be provided to indicate vacuum in the casting box manifold.

A limit switch 74 of known construction is mounted adjacent the side of the casting box 2 (Fig. 4). The operating lever 75 of the switch 74 is engaged and moved to a switch closing position by a bracket 76 on the casting box 2 as the box moves to its mold space closing position adjacent the core 1. Thus the switch 74 is closed only when the casting box is in closed relation to the core.

Referring to Fig. 10, control current from a source designated A.-C. is connected in a circuit including the wire 77, the limit switch 74, the wire 78, the vacuum contacts 71, the wire 79 and the solenoid of a solenoid valve 80 in the air supply pipe 46. The solenoid valve 80 is of known construction and opens when energized so as to admit compressed air through the pipe 46 leading to the inlet port of the control valve V. With this arrangement, the metal pump 12 can be operated to perform a mold charging stroke only if a matrix is in the casting box and the casting box is in closed relation to the core and then only if the last previously cast plate has been removed from the mold space by turning the core through a half revolution.

A modified form of apparatus for carrying out the invention is illustrated in Figs. 11-15. This modification is applied to a known form of plate

casting apparatus employing a semi-cylindrical core 81 carried by rollers 82 running on tracks 83, the core 81 being linked to the frame 84 by pivoted links 85 so that the core may be moved from a vertically closed position adjacent the stationary casting box 86 to a horizontal open position in which the cast plate 87 is discharged. The core 81 is shown in broken lines in the closed position and in full lines in the open position in Fig. 11. A foot pedal 88 may be provided to start the core 81 away from the casting box 86 after a plate has been cast and the usual handle 89 is provided for tilting and returning the core.

The melting pot 89 is disposed in a furnace 90 and is provided with a single stroke pump 91 connected to deliver molten type metal to the mold space between the casting box 86 and the core 81 through a spout 92. The pump 91 is operated by a counterweighted pump lever 93 linked to the pump piston rod 94 and pivoted to a bracket 95. An air cylinder 96, pivotally supported at its lower end in a bracket 97, has a piston rod 98 pivotally connected to the pump lever 93, as shown. A tube 99 surrounds the piston rod 98 and its upper end acts as a stop for engagement by a nut 100 threadedly engaging the rod 98 and adjustably threaded to fix the magnitude of the metal charging stroke. Air hoses 101 and 102 lead, respectively, to the lower and upper ends of the air cylinder 96 from the control valve V'. The valve V' is of the same construction as the valve V, described above. It acts to supply compressed air from the air supply pipe 103 to the hose 101 and so to operate the pump 91 through a metal charging stroke when the valve handle 104 is moved forwardly, as shown in Fig. 11, and to supply compressed air to the hose 102 and so operate the pump through its return stroke when the handle 104 is returned to a rearward position when released.

Referring to Figs. 12, 13 and 14, the valve V' and its control mechanism are mounted on a bracket 105 secured to the machine frame 84. A slide 106 carrying a rod 107 is slidably mounted in the bracket 105. An adjustable screw 108 extends from the end of the rod 107 and is locked in adjusted position by a nut 110. A spring 111 connected between the slide 106 and the bracket 105 biases the slide and the rod 107 to move to the left to the position shown in Figs. 11 and 12. A stop bar 112 is pivotally mounted on the bracket 105 and is biased by a spring 113, to move counterclockwise against a stop pin 114, in which position the bar 112 prevents pump operating movement of the valve handle 104 (Fig. 12). A latch bar 115 is pivotally mounted on the slide 106 and is biased by a spring 116 to turn counterclockwise toward a position engaging a stop pin 117. When in this position, the free end of the latch bar 115 is in line with a pin 118 on the stop bar 112 so that movement of the slide 106 to the right moves the stop bar 112 to the right and out of the path of the valve handle 104, as shown in Fig. 13. A hub 119 on an arm 120 connected to the core 81 carries the shaft of the roller 82 and is aligned with the end of the screw 110. When the core 81 is moved to its vertical or closed position adjacent the casting box 86, the hub 119 engages the screw 108 and moves the rod 107 and slide 106 to the right against the bias of the spring 111 to the position shown in Fig. 13. During this movement, the latch bar 115 moves the stop bar 112 to the right out of the path of the valve handle 104, and this handle can thereafter be pulled forward to cause

a metal charging stroke of the pump 91. This forward movement of the handle 104 moves the latch bar 115 out of the path of the pin 118 and the spring 113 returns the stop bar 112 to a position in which it engages the side of the handle 104. Then, as the handle 104 is returned to its rearward position to cause the return stroke of the pump 91, the stop bar 112 snaps under the lever 104 and prevents its subsequent movement to cause a second metal charging stroke of the pump. When the core 81 is tilted to discharge the cast plate 87, and thereafter returned to closed position, the latch bar 115 again moves the stop bar 112 out of the path of the valve handle 104 and so sets the mechanism in condition for a subsequent metal charging stroke of the pump 91.

The casting box 86 of the apparatus shown in Fig. 11 is provided with a vacuum manifold and holes for drawing the matrix against the concave casting box surface, as has been explained above in connection with Fig. 9. The pipe 121 connecting the source of vacuum 122 with the casting box 86 is also connected with a cylinder 123 carrying a spring biased piston 124 that closes the electrical contacts 125 when the presence of a matrix in the casting box builds up a vacuum in the pipe 121, the contacts 125 being open if no matrix is present.

When the handle 104 of the valve V' is moved to the charging stroke position, if there is a matrix in the casting box 86, the contacts 125 are closed and the solenoid valve 126 is energized through the circuit shown in Fig. 15, admitting compressed air to the inlet of the valve V' through the pipe 127. The compressed air passes through the hose 101 to the lower end of the air cylinder 96, lifts the plunger 98 and so causes a charging stroke of the pump 91. Release of the valve handle 104 permits return of the valve to the return stroke position in which compressed air is delivered through the hose 102 to the upper end of the air cylinder 96, lowering the piston rod 98 and returning the pump to a position in readiness for another charging stroke. A second operation of the valve handle 104 is prevented by the stop bar 112 until after the core 81 has been opened for removal of the casting plate therefrom. Since the stop bar 112 is moved out of the path of the valve handle 104 only when the core 81 is closed against the casting box, the metal charging stroke cannot take place until the mold space is closed.

From the foregoing description, it will be apparent that the invention provides mechanism for the safe power operation of the molten type metal pump, the mechanism being such as to prevent the pumping of metal with the mold space open or with a charge of metal or a cast plate in the mold space. Where a vacuum is employed to hold the matrix against the concave casting box wall, the mechanism of the invention also prevents the pumping of metal into the mold space unless the matrix is in position. It will be understood that in plate casting machines lacking this vacuum feature, the vacuum responsive control described will be omitted without change in the structure or functions of the other above-described safety mechanisms.

We claim:

1. In a stereotype plate casting machine of the type including relatively movable mold forming members having surfaces forming a mold space therebetween upon movement of one of said members toward the other, a metal pump for de-

livering molten metal to said mold space, a source of suction and ducts connecting said source to the mold forming surface of one of said mold forming members for seating on said surface a matrix placed over the mouths of said ducts, a power unit for operating said pump, and a conduit for supplying operating energy to said power unit, the improvement which comprises the combination therewith of a valve in said conduit normally closed to prevent the flow of energy to said power unit, and a pressure responsive device connected to said mold member ducts and responsive to a drop in pressure therein resulting from the closing of the mouths of said ducts by a matrix seated on the mold forming surface of said member for opening said valve.

2. In a stereotype plate casting machine of the type including mold forming members having surfaces relatively movable to discharge a cast plate from and reform a mold space therebetween, a pump for delivering molten metal to such mold space, a source of suction and ducts connecting said source to the mold forming surface of one of said mold members to seat on such surface a matrix placed over the mouths of said ducts, a power unit for operating said pump through a metal charging stroke and a return stroke, a conduit for conducting operating energy to said power unit, and a control device connected in said conduit and including a handle movable to a charging position to energize the power unit to perform a metal charging pump stroke and to a return position to perform a return pump stroke, the improvement which comprises the combination therewith of a bar movably mounted adjacent said handle and movable into and out of a position blocking the path of movement of said handle to the charging position, means biasing said bar to move to said blocking position, a movable element adapted upon movement to move said bar out of said blocking position, said movable element being disposed in the path of and adapted to be moved by mold reforming movement of one of said relatively movable mold forming members, a valve in said conduit normally closed to prevent the flow of energy to said power unit, and a pressure responsive device connected to said mold member ducts and responsive to a drop in pressure therein resulting from the closing of said ducts by a matrix placed over the mouths of said ducts for opening said valve.

3. In a stereotype plate casting machine the improvement as set forth in claim 2 which includes latch means for engaging and holding said bar out of blocking position and movable when said handle is moved to the charging position for releasing said bar for return by said biasing means to its handle blocking position when said handle moves to its return position.

4. In a stereotype plate casting machine of the type including a concave semi-cylindrical casting box, a cylindrical core adjacent said casting box and rotatable to remove a cast plate from the mold space therebetween, a metal pump for delivering molten metal to such mold space, a power unit for operating the pump through a mold charging stroke and a return stroke, a conduit for conducting operating energy to said power unit, and a manually operable control device in said conduit having a handle movable to a charging position in which operating energy from said conduit operates said power unit to cause a charging pump stroke and to a return position in which operating energy from said conduit operates said unit to cause a return pump stroke,

the improvement which comprises the combination therewith of a bar movably mounted adjacent said handle and movable into and out of a position blocking charging movement of said handle, means biasing said bar to move to said blocking position, and a movable latch lying in the path of movement of said handle to its charging position and engageable by said handle and engageable with said bar to hold said bar out of said blocking position until said latch is engaged and displaced by movement of said handle to its charging position.

5. In a stereotype plate casting machine of the type including mold forming members relatively movable to discharge a cast plate from and reform a mold space therebetween, a metal pump for delivering molten metal to such a mold space, a power unit for operating the pump through a metal charging stroke and a return stroke, and a control device for controlling the energization of said power unit and including a handle movable to a charging position in which the power unit is energized to perform a metal charging pump stroke and to a return position in which said power unit is energized to perform a return pump stroke, the improvement which comprises the combination therewith of a bar adjacent said handle movable into and out of a position blocking the path of movement of said control device handle to the charging position, means biasing said bar to move to said blocking position, latch means adapted to engage and hold said blocking bar out of blocking position after each mold reforming movement of one of said relatively movable mold forming members, said latch means being engageable and movable by said handle when said handle is moved to the charging position for releasing said bar for return by said bar biasing means to its handle blocking position when said handle moves to its return position, and means biasing said latch means toward its blocking bar holding position.

6. In a stereotype plate casting machine the improvement set forth in claim 5 in which said blocking bar is pivotally mounted and in which the latch means is a pivotally mounted latch lying in the path of movement of said handle to the charging position when so holding the bar out of blocking position.

7. In a stereotype plate casting machine of the type including a rotary cylindrical core, a concave cylindrical casting box adjacent said core and movable toward and away from said core to

close and open a mold space therebetween, and means for rotating said core to remove a cast plate from the mold space, the improvement as set forth in claim 5 which includes a pin mounted adjacent said blocking bar and movable into engagement with said blocking bar to move said bar out of its handle blocking position, and means carried by said rotary cylindrical core and engageable with said pin upon plate-removing rotation of said core to move said pin into engagement with said blocking bar to move said blocking bar out of handle blocking position.

8. In a stereotype plate casting machine of the type including a casting box and a core movable toward said casting box to form a mold space and movable away from said casting box to remove a cast plate from said mold space, the improvement as set forth in claim 5 which includes a slide mounted adjacent said handle and movable by said core when said core is moved toward said casting box to form a mold space, said latch means being mounted on and carried by said slide.
